UNITED STATES PATENT OFFICE.

WM. F. WARBURTON AND C. E. LOVETT, OF PHILADELPHIA, PENNSYLVANIA.

MANUFACTURE OF HATS.

Specification of Letters Patent No. 27,848, dated April 10, 1860.

To all whom it may concern:

Be it known that we, W. F. WARBURTON and C. E. LOVETT, both of the city and county of Philadelphia and State of Pennsylvania, have invented a new and useful Improvement in the Manufacture of Hats; and we do hereby declare the following to be a full, clear, and exact description of the same.

10 Our invention consists of a process, fully described hereafter, of attaching the lining to the interior of a hat by means of an elastic cement simultaneously with the finishing of the exterior of the hat by the application of heated irons, so that the body of the hat may be rendered elastic and the interior smooth and uniform without any other manipulation than that required for finishing the exterior of ordinary hats.

20 In order to enable others skilled in the art to practice our invention, we will now proceed to describe the manner in which to carry it into effect.

In the accompanying drawing which 25 forms a part of this specification Figure 1, represents a vertical section of our improved hat. Fig. 2, an exaggerated sectional view of part of Fig. 1, showing the different materials of which the hat is composed.

30 The hats to the manufacture of which our improvement is most applicable, are those which have bodies which require finishing on the outside with heated irons, such as some classes of felt hats and hats which 35 have stiffened bodies.

In applying our improvement to the latter class of felt hats, the body is saturated with the usual stiffening material, reduced to the desired form by the well known process of blocking and ironing, and the exterior of the body coated with shellac varnish for receiving the plush covering. A lining of thin leather, any woolen fabric, or other material usually employed for the purpose, 45 and having any desired ornamental figures and designs on its surface, is then selected and its unornamented surface coated with a preparation of gum elastic or any other substance or combination of substances 50 which possess the two properties of close adhesion when applied under heat and pressure, and elasticity when cold. The lining is then spread over the whole interior of the body with its prepared surface in contact 55 with the felt, when the body is ready to be submitted to the process of finishing. This

is accomplished by applying a heated iron to the plush cover on the outside of the body, the heat causing the shellac preparation to melt and rendering it an adhesive medium 60 for securing the plush cover to the body, at the same time the heat striking through the felt will melt the gum elastic or other preparation with which the lining is coated, and this heat combined with the pressure of the 65 iron will cause the lining to adhere closely to the inside of the felt body which is now complete. In ordinary hats the lining is loose and detached from the body, the rigidity of the hat depending upon the coating 70 of shellac varnish. Now the latter, especially after the spirit with which it is prepared has evaporated, is very brittle and readily granulates, so that the hat receiving a blow or any undue pressure the body will 75 break, the shellac granulating at the point where the breakage takes place, and the hat consequently becoming bulged and presenting an unsightly appearance. By securing the lining to the body of the hat through 80 the medium of an elastic adhesive cement, not only is additional strength afforded, but if the hat receives a blow, the part struck will through the elasticity of the cement, instantly recover its original position, so that 85 the body of the hat remains unbroken and free from unsightly bulges.

As regards the internal appearance of hats manufactured after our improvements, it will be readily seen that any variety of fancy 90 linings may be used to suit the taste of the maker, at the same time the uniformity with which the lining is spread over the interior surface of the hat renders it more pleasing to the eye than the ordinary detachable lining which in time becomes crumpled and unsightly.

We claim as our invention and desire to secure by Letters Patent—

The process of attaching the lining to the 100 interior of the hat by means of an elastic cement simultaneously with the finishing of the exterior of the hat as herein set forth.

In testimony whereof, we have signed our names to this specification in the presence of 105 two subscribing witnesses.

WM. F. WARBURTON.
CHAS. E. LOVETT.
